ROOFING ELEMENT AND ASSEMBLY
THEREOF

Norman P. Harshberger, Scarsdale, N. Y., assignor to Bakelite Building Products Co. Inc., New York, N. Y., a corporation of Delaware

Application January 8, 1934, Serial No. 705,811

16 Claims. (Cl. 108—7)

This invention relates to roofing and siding material comprising elements adapted to be arranged in overlapping courses in simulation of shingles and more particularly of tiles and to present a pleasing and ornamental appearance.

Roofing materials generally comprise those made of rigid materials such as slate and tile, as well as elements formed of cementitious mixtures, and those made of waterproofed fibrous material commonly known as composition roofing. The former materials are heavy and necessitate special understructures for supporting the roof. Further, they are relatively expensive and are generally limited to use on costly houses. The composition material is more generally employed and attempts have been made to simulate a surface of curved tile effects by using substantially flat strips of this material and shaping the exposed edges with curved tabs. To make the effect of heavy butt edges of built up elements more pronounced the surface of the material at the edges has been contrastingly colored to produce heavy artificial shadow lines and in certain instances the tabs themselves have been so cut to present lines tending to depict similar depth effects to the eye. These methods have not been particularly satisfactory for where edge bands have been employed these rapidly fade or become discolored due to the action of the weather, and where the result has been obtained by shaping it usually has been at the expense of the resistance of the tabs to thwart lifting in the wind. Also, the processes employed are not simple ones. In any instance, in order to obtain suitable effects it is desirable for the tabs to be of considerable depth and except where they are shallow as where thatch effects are to be secured, there results a considerable tendency to curl and lift in the wind and permit rain and the like to drive under them.

It is therefore an object of the present invention to overcome the faults and objections of prior roofing elements as well as to provide a simple, inexpensive element that will form an effective and attractive surface in which curling and winding up will be a minimum and one that is well adapted for the purpose described.

In my copending application Serial No. 483,311, filed Sept. 20, 1930, and granted as Patent No. 1,943,258 on January 9, 1934, I describe a method of making rigid roofing elements in which wool, cotton rags, hair, asbestos fibres or paper are first manufactured into a felted material to form a base which is subsequently treated with a starch-containing solution and is then dried,

cut, as desired, into sections and ironed into rigid shapes. These are thereafter impregnated with a suitable waterproofing compound such as a low melting point asphalt, coated with a layer of an adhesive material such as a high melting point asphalt and/or synthetic resins and surfaced with such granulated materials as mineral particles of slate, shale, crushed brick, etc., which are embedded therein and provide the finished elements with an attractive appearance.

This application is a continuation-in-part of said copending one and particularly relates to a portion wherein substantially flat or shaped elements with or without the stiffening treatment are made, provided with locking members and assembled according to arrangements which, together with the elements themselves, will herein-after be more fully described.

More specifically the objects of my invention may be enumerated as:

To provide a substantially flat shingle element of uniform thickness, which may also be rigid and to arrange a plurality of such elements as to produce effective heavy butt effects and particularly curved tile simulations in assembly.

To provide elements having a plurality of depending tabs in which the tabs are provided with locking members and receiving means to lock down the weather exposed portions.

To provide a surface assembly wherein units having tab formations are laid in wide spaced relationship with an element in one course overlapping two adjacent elements in the same course in such a manner as to present tabs of double thickness with the individual layers offset with respect to each other to form a heavy butt effect.

To provide a roofing element that will provide the characteristics of rigid tiles at a much lower cost.

These, and other objects and features of the invention, relating to the improved shingle element and assembly thereof, and all its parts and combinations will in part be obvious and in part be pointed out in the subsequent detailed description and in the claims, taken in conjunction with the accompanying drawing, wherein

Fig. 1 is a plan view of a shingle element of my invention;

Fig. 2 is a plan view of a portion of a surface covering formed by a plurality of elements and embodying a feature of my invention;

Fig. 3 is a plan view of a modification of the element of my invention;

Fig. 4 is a plan view of another surface cov-

ering showing an arrangement obtained by the elements of my invention;

Fig. 5 is an end view of an element;

Fig. 6 is a front elevation of elements with filler 5 pieces, and

Fig. 7 is a side sectional elevation on line 7—7 of Figure 2, of elements with filler pieces.

The shingles of my invention may be made of any of the well known composition roofing materials described above and are preferably cut from a continuous finished sheet thereof. However, they may be made, if desired, of similar material wherein during the processing there has been included the steps of adding a starch-like stiffening ingredient and ironing into a rigid condition in one or more portions before or after cutting the sheet into individual sizes. Also the amount of stiffener added may be controlled so as to obtain a degree of stiffness appropriate to 10 the type of element fabricated, this being particularly desirable where the elements are provided with locking members in which a degree of flexibility may be desirable.

Fig. 1 illustrates the preferred form of my 25 shingle unit 2 which preferably comprises a substantially flat body portion 4 having a pair of similar curved and preferably substantially equal tabs 6 and 8 depending from its lower part and having a recess 10 therebetween which is preferably of 30 greater width than the tabs. Adjacent the tabs and substantially connecting the edges thereof the body portion preferably has two opposite substantially parallel sides 12 and 14 which are also substantially straight. The upper edge 16 of the 35 element is formed with a curved tab projection 18 and has recesses 20 and 22 on either side adjacent thereto. It will be noted that this edge is substantially parallel and homologous to the lower edge 24 and that the recesses of one edge are complementary to the tabs of the other edge. I prefer this since with the respective sides interfitting, the elements may be cut from a continuous web without waste and further it permits a considerable saving of material to be made in assembly 45 where a substantially uniform lap is thereby obtainable.

Further, the elements may be said to be divided into a number of sections *a*, *b* and *c*, each substantially the width of a tab and it will be seen 50 that the center section is of considerably greater depth than width and of greater width than the end sections. I prefer the ratio of depth to width to be substantially three to one or greater and preferably make the depth of the recess formed 55 by the center section substantially equal to its width. These proportions are desirable since, by them, I may more nearly simulate a roof of rigid Spanish tiles, and furthermore, the end sections determine the amount of side lap in assembly and 60 it is desired to keep this to a minimum commensurate with adequate protection and good appearance. However, I do not limit myself to these proportions, to the tab proportions illustrated, or to only curved formations and straight and vertical sides since the tabs may be equal or greater 65 in width than their recesses and the proportions of length and width may be any desired. Also the sides may be oblique and of other shapes.

I may also provide the tab portions of the end 70 sections of my units with locking members and receiving means, especially where they are made of wholly flexible material without stiffening means in order to lock the edges and prevent the exposed portions from curling or blowing up in 75 the wind and to permit me to make larger ex-

posures to the weather than would otherwise be possible. In Fig. 1 the locking means are preferably positioned substantially midway the depth of the tabs, i. e. between the lower edge of the tab and the upper edge of the recess, and at opposite 5 portions thereof, the locking tongues 26 and 28 being preferably at the outer ends of the elements and the receiving means 30 and 32 being preferably in the sides of the tabs adjacent the recess between tabs. The tongues may be formed by slits 10 or cuts 34 and 36, one of which may be substantially horizontal and the other substantially vertical so that the tongue is formed with a finger portion which preferably project upwardly, and the receiving means are formed preferably by 15 substantially horizontal cuts 38 in the edges adjacent the recess. It should be noted that in this figure the lower extremity 39 of the vertical tongue cut is lower than the level of the receiving means 30 and the purpose of this will be herein- 20 after explained. Also, while I have illustrated the locking members and receiving means as formed by slits or single cuts, these may also be slots, and, further, the locking tongues may be formed by a cut or series of cuts wholly within the 25 tab portion and the receiving means may also be an interior slit or opening. I may also make the tongue members of curved outline, tapered, or provide them with tapered tips and the receiving means may be shaped other than straight or may 30 also be a tongue that may be depressed in assembly. These variations offer advantages of greater facility in assembly and in certain instances it is preferred to substitute them for those illustrated.

The elements I have thus described may be 35 assembled as in Figure 2 to simulate a roofing surface formed of a plurality of curved tile shapes. The elements in each course may be laid in wide spaced relationship, the space between them being substantially the width of section *b*, and thereafter, additional elements are laid in the same course to fill the spaces and these form bridging members therebetween. Since the individual elements are spaced apart such distances that the end sections *a* and *c* of 40 the bridging elements completely sidelap the end sections *c* and *a*, respectively, of two underlying elements in the same course, the exposed edge of each course presents a plurality of alternating tabs and recesses in which the tabs formed are of 45 double thickness and the recesses are of single thickness. Such recesses may be substantially filled by using elements such as the element 61, Figure 5, which has an integral layer 62, by following the teaching of my copending application 50 Ser. No. 358,586, filed April 27, 1929. The double edge thickness formed by the tabs produce a considerable shadow in assembly and to enhance this effect I may arrange the bridging elements in 55 each course substantially offset to the vertical so that the formation of elements in each course thus formed present stepped edges 40 formed by the lapped and offset strata of adjacent elements. Such an arrangement greatly increases the shadow effect produced and makes the same 60 more realistic since it produces one that is greatest in the supposed valleys 42 between tiles and tapers off to a lesser degree at the supposed crest 44 of the tiles. The elements may be secured to the roof structure by fasteners, for 65 instance, the nails 46 and 48 which locate the wide spaced elements and by the nails 50 and 52 which secure the bridging elements and also pass through the adjacent underlying units. The fasteners are covered by the bridging elements of 70 75 75

the next overlying course of units. Where the units are not provided with tab locks it is preferred that they be somewhat stiff as the bridging elements are unsecured at the lower weather edge unless other securing means are provided. Where the tabs are provided with locking members as shown in Figure 1, the locking tongues 26 and 28 are received by the recesses or receiving means 32 and 30, respectively, of the two adjacent underlying elements in the same course and the lock is effected by moving the bridging element in a direction normal to the line of the course. Due to the relative positions of the receiving means 30 and 32 and the lower extremities 39 of the locking tongues 26 and 28 when the bridging element is pulled into position the tab portions will be located as shown at 40 in Figure 2, forming as has been described, a stepped arrangement. The advantages of the locking arrangement are obvious, the bridging elements may each be secured to the roof deck by a single nail as at 54, Fig. 4, the tabs interlocking with the lower portions of the two adjacent underlying elements and covering the nails 46 and 48 which secure these elements to the under structure. Thus the entire weather edge formed by the course of elements is securely held down and prevented from curling or blowing up in the wind.

In Fig. 3, I have shown an element 56 similar in shape to that of Figure 1, but in which the sections formed by the tabs and recesses have been definitely divided by lines of demarcation, 58 and 60. Such means of separation may be formed by colored stripes, by raised ridges, by scored lines or the sections may be surfaced with materials of contrasting effects. Also, it will be noted that I have located the locking members on this element such that the lower extremity 39 of the vertical slot 36 forming the locking tongue members 26 and 28 are on a level with the opposite receiving means. These elements, when assembled in wide spaced relationship and interlocked, form a surface as shown in Figure 4, wherein each tab formation is of a double thickness but wherein the overlapping portions are coincident. In this manner alternating tabs and recesses in each course form a single zig zag line parallel to the course. The particular advantage of the lines of demarcation are that the bridging elements provided with artificial lines to aid in giving them curved effects. It should be noted that where the elements are arranged in wide spaced fashion such assembly lends itself to different and effective appearances on the roof. For instance, one result is obtained as shown in Fig. 2 where the courses of elements are arranged such that the bridging elements in each course lie one above the other. A second and entirely different effect is obtainable as shown in Fig. 4 where the alternate courses are so arranged that the bridging elements in adjacent courses are staggered in relation to each other. Also I desire it to be understood that while I have illustrated assemblies wherein the elements are laid wide spaced these may be laid in side-lap fashion using the same locking means for locking down the exposed portions, there resulting in such an assembly a different appearing surface from that shown. Further, while the elements illustrated show only a pair of depending tabs such elements may be of greater length and may have as many tabs as may be desirable.

From a consideration of the foregoing description it will be seen that I have produced an element that may be economically fabricated, that

is simple in assembly, and that forms a particularly desirable and effective roof. Modifications other than those illustrated or described will present themselves to those skilled in the art, and I desire that the invention be construed to cover equivalents and as broadly as the claims taken in conjunction with the prior art, may allow.

I claim:

1. A roofing element comprising a strip of material having a pair of substantially straight and opposite edges and having a third lower edge formed with an ogee curve comprising a pair of similar curved tabs and a curved recess therebetween, said tabs being positioned adjacent said substantially straight edges and having their edges substantially prolongations thereof, and said recess having a width greater than said tabs and of substantially one third the depth of the element measured normal to a median through the tabs on the lower edge and said elements adapted when laid to simulate a surface of formed tiles.

2. A roofing element comprising a body portion having a plurality of similar tabs projecting from an edge thereof, one of said tabs having a receiving means comprising a slot positioned in its side edge portion and another having a locking means comprising a tongue positioned adjacent a similar edge portion to interlock with the receiving means of an adjacent shingle.

3. A roofing element comprising a body portion having a lower edge formed with alternating tabs and recesses, locking and receiving means positioned in opposite edge portions of said tabs and substantially midway their depth the locking means on the tab of one shingle adapted to interlock with the receiving means on a tab of an adjacent shingle.

4. Roofing elements having the general shape of a parallelogram comprising body portions having two substantially straight side edges, and two other opposite and substantially complementary edges of wavy outline presenting alternating tabs and recesses, certain tabs having a tongue in the side edge thereof extending in the direction of the depth of the shingle and a slot, said tongue being engageable with the slot of a similar element in assembly.

5. A roofing element comprising a body portion having a lower edge formed with a pair of shingle size tabs separated by a recess of greater width than said tabs, there being receiving means positioned in opposite tab edge portions of the recess and locking means adjacent other edge portions of the tabs.

6. A roofing element comprising a body portion having end edges; a pair of tabs depending from the lower edge portion of the body separated by a recess of greater width than the tabs, the edges of said tabs forming substantially prolongations of the end edges and said tabs and recess determining three sections, the depth of the sections being at least three times the width of the section determined by the recess, and the depth of the tabs being substantially equal to the width of the recess, said elements adapted to be laid with a tab of one element lapping a tab of an adjacent element in the same course to simulate an assembly of formed tiles.

7. A roofing element having a lower weather edge formed with curved tabs, said tabs having in an edge portion thereof and removed from the lower end thereof, an upwardly projecting tongue and a receiving means, said tongue being engageable with the receiving means on the tab of

- an adjacent element in assembly to lock down said weather edge.
8. A roof covering comprising a plurality of elements each presenting lower tab edge formations, 5 said elements being laid in wide space relationship with one element overlapping two adjacent elements in the same course and with the end tabs of the overlapping element substantially coincident with the end tabs of the adjacent under- 10 lying elements so as to present a tab edge of double thickness, the tabs of one element serving to register the overlying tabs of another.
9. A plurality of shingles assembled on a roof in courses, each shingle comprising a body portion having substantially straight side edges and 15 a pair of tabs of curved outline depending from the lower edge thereof, and having a recess therebetween, said tabs and recess each determining a section of the element, and said elements being 20 arranged in a course with certain elements wide spaced, and with other elements bridging the wide spaced elements and having their tab determining sections substantially coincident with 25 similar sections of the wide spaced elements to form a substantially continuous curvilinear butt edge across the course, and said edge, and the side edges of the bridging elements aiding in simulating a formed tile construction.
10. A roof covering comprising a plurality of 30 elements assembled in courses, each element having substantially straight side edges and a lower weather edge formed with alternating tabs and a recess of curved outline and of greater width than the tabs, said elements being arranged in a 35 course with their tabs overlapping the tabs of adjacent elements so as to present a continuous weather edge of wavy outline across the course said elements when laid simulating a roof of formed tiles.
11. A plurality of shingle elements assembled 40 in courses, said elements comprising body portions having lower weather edges formed with curved tabs and recesses of substantial depth, said elements being arranged in a course with the 45 tabs of adjacent elements overlapping and with the side edge portions thereof in registration and determining the amount of overlap and with certain elements offset substantially to the vertical so as to effect a weather edge in the course comprising alternately single edges of the recesses 50 and double edges of the tabs.
12. A plurality of shingle elements assembled 55 on a roof, said elements comprising body portions having a plurality of tabs projecting from edges thereof, said tabs having locking and receiving means positioned adjacent opposite edge portions thereof and comprising respectively tongues and slots, said elements being laid in courses with the tab portions of adjacent shingles 60 in lapped relation and, with the locking means on the tab of one element engaged with the receiving means on the tab of an adjacent lapped element so as to lock down the tabs.
13. A plurality of shingles assembled on a roof, said elements comprising body portions having a pair of tabs depending from an edge thereof, and having a recess therebetween, said elements also having receiving means comprising slots positioned on the tabs adjacent opposite edge portions of the recess, and locking means comprising tongues positioned adjacent other edge portions of the tabs, and said elements being assembled in courses with certain elements wide spaced and 10 with other elements bridging the wide spaced elements, said bridging elements having their locking tongues engaged with the receiving means of their underlying elements so as to lock down the weather edge of the course. 5
14. A roof covering comprising shingles arranged in overlapping rows, each shingle comprising a body portion having a lower edge formed with a pair of tabs and having a recess therebetween, said tabs and recess each determining a section of the element extending the depth thereof, and the section determined by the recess having upon its reverse side an integral layer extending substantially the length of said section and substantially of equal thickness, and said elements being arranged in a course with certain elements wide spaced, and with other elements bridging the wide spaced elements and having their tab determining sections overlapping similar sections of adjacent elements in the same 30 course with the side edge portions of the lapping tabs in substantial alignment, and said integral layer substantially filling the space between the spaced apart elements.
15. A roofing element comprising a body formed with locking and receiving means in a lower portion thereof, said means comprising a tongue and a slot, said tongue being removed from the lowermost point of the body and having a portion that will retard its further movement in the slot of a 40 similar element when laid, and said portion being so positioned in relation to the slot, that a plurality of said elements may be laid in assembly with adjacent elements in the same course lapped and interlocked and offset with respect to a straight 45 median line through the course to form a stepped arrangement of the lapping portions at the lower edge of the course. 40
16. A roofing element comprising a body having a lower portion formed with tabs, one of said 50 tabs having a locking means and another a receiving means on similar edge portions and substantially removed from the lower edges thereof, said locking and receiving means comprising respectively a tongue and a slot, and said tongue having a portion that will retard its further movement in the slot of a similar element and so positioned in relation to the slot as to cause the tabs of adjacent shingles when lapped in assembly with the tongue of one interlocked with the slot 55 of the other, to be offset and form steps thereof. 60

NORMAN P. HARSHBERGER.
